HAROLD P. BROWN, OF NEW YORK, N. Y.

METHOD OF AND APPARATUS FOR MIXING CONCRETE.

1,297,081.

Specification of Letters Patent. Patented Mar. 11, 1919.

Application filed December 24, 1914. Serial No. 872,350.

To all whom it may concern:

Be it known that I, HAROLD P. BROWN, a citizen of the United States, residing in the borough of Manhattan of the city of New York, in the county of New York, in the State of New York, have invented certain new and useful Improvements in Methods of and Apparatus for Mixing Concrete, of which the following is a specification, reference being had to the accompanying drawings, which form a part hereof.

This invention relates to the method of and apparatus for mixing and placing concrete or similar cementitious material and is concerned particularly with the conveying and placing of mixed cementitious material containing sand, stone and cement. It is comparatively easy to place grout which is substantially of the consistency of cream but it is very difficult to place concrete, which, in its wet state, is a plastic solid and contains segregated rock material. It has been proposed to mix the dry constituents of cementitious materials first and then convey them through a suitable conduit, as by means of a blast of compressed air, toward the point of discharge, and hydrate the mixture at the instant of discharge. In this way it has been sought to minimize the dangers of clogging. By the present invention, it has been sought to overcome all of the difficulties, expense and disadvantages incident to former methods and apparatus and provide a new and improved method of and apparatus for mixing concrete thoroughly and then granulating the mass by means of a fluid blast and conveying it through a conduit to an improved nozzle through which it is discharged in placing. In using the word "fluid" I wish to have it understood in its broadest sense to include any suitable flowing medium, particularly gas, vapor, air and steam. The invention seeks particularly to insure a uniform mixture of the cementitious materials before they are delivered to the conveyer and to subject them to the action of preferably an elastic gaseous element, for example steam, which may or may not serve as the impelling force, and which has the peculiar property of accelerating hydration of the mixed mass to just the proper degree, and, after the mass has been placed and pressure released, of accelerating drying and crystallization, thereby insuring a strong, dense deposit after a comparatively short period of

time for setting. The invention has for a further object the provision of an improved mixer whereby the materials are thoroughly agitated and brought into uniform and intimate association throughout the batch, the mixing devices being of such a character as to scrape the elements thereof continuously and prevent the setting of concrete at any point within the mixer and, at the same time, to convey the material toward the point of discharge. Still another feature of the invention resides in the provision of an improved nozzle for applying the concrete, this nozzle being susceptible of ready manual manipulation for the purpose of dislodging such material as tends to clog therein. Other objects will appear herein-after as the description proceeds, reference now being had to the accompanying drawings for a detailed description of a preferred embodiment of the invention. In the drawings—

Figure 1 is a view partly in side elevation and partly in vertical section of a complete portable apparatus embodying the invention, the conveying conduit and the nozzle therefor being omitted.

Fig. 2 is a view in end elevation of the apparatus shown in Fig. 1.

Fig. 3 is a fragmentary view in transverse vertical section taken through the mixer drum shown in Fig. 1.

Fig. 4 is a fragmentary view on a somewhat larger scale taken on the plane indicated by the line 4—4 of Fig. 1 and looking in the direction of the arrows.

Fig. 5 is a fragmentary view in perspective showing the mixing blades mounted on their supporting shaft and carrying the improved auxiliary agitating and scraping devices.

Fig. 6 is a detail view in perspective and on a somewhat larger scale, of the mixing blades.

Fig. 7 is a fragmentary view in vertical section taken through the discharge head of the mixing drum and showing particularly the valve for controlling the passage of material from the drum into the conveyer.

Fig. 8 is a view in side elevation and purely conventional, of a complete plant for practising the improved method.

As shown in Fig. 1, the improved mixing apparatus comprises generally, a stationary drum *a* in which are disposed operatively mixing blades *b* secured on a shaft

c to which rotative movement is imparted through a gear *d* keyed on one end thereof and in mesh with a driving pinion *e* driven by a suitable motor *f* which is provided with the usual controlling and reversing devices. The elements referred to may conveniently be mounted on a portable carriage frame *g*, the wheels *g'* thereof, being preferably so proportioned with respect to each other as to support the drum in an inclined position to facilitate the discharge of the mixed material therefrom, as will appear hereinafter.

The present invention seeks to provide for a more uniform mixing of the cementitious materials and to provide an apparatus which shall be efficient in operation and entirely suitable for the successful practice of the improved method of mixing and placing concrete. To this end, the drum *a*, the mixing blades *b* and many of the associated parts possess novel characteristics. The constituents of the concrete may be fed into the drum *a* from a hopper *a'*, indicated in dotted lines in Fig. 1, and conveniently supported on a hollow dome *a²* with which it communicates through an opening *a³* formed in the dome and controlled by a suitable flap valve *a⁴* which may be held in closed position against the action of gravity by means of a rod *a⁵*, the free end of which is within convenient reach of the operator. The material passes through the dome *a²* and an opening *a⁶* formed in the wall of the drum *a*, into the drum, where it is engaged and mixed uniformly and thoroughly by the rotating mixing blades *b* and their auxiliary mixing devices, as will appear later, and conveyed steadily toward a suitable discharge opening *a⁷* formed in the remote head *a⁸* of the drum. Under some conditions of use it may be desirable to introduce the material into the drum through a filling opening *a⁹* formed in the same head *a⁸* of the drum as the discharge opening *a⁷*. The filling opening *a⁹* may be controlled conveniently by a suitable gate valve *a¹⁰*.

The devices by which the mixing is effected after the material is introduced into the drum, will now be considered. The rotatable supporting shaft *c* for the mixing blades *b* may be journaled adjacent its ends in suitable split bearings *c'* carried on brackets *a¹¹* which are secured to the heads *a⁸* and *a¹²* of the drum *a*, the bracket *a¹¹* at that end of the shaft *c* which carries the driving gear *d* being so spaced with respect to the shaft and the bearing *c'* as to permit the interposition of spacing blocks *h* which, when removed, permit the disassembling and lateral removal of the bearing. It is evident that the bearing *c'* at the other end of the shaft *c* may be slipped off from the shaft very readily. To insure a gastight and grit-tight union between the shaft *c* and the re-

spective heads *a⁸* and *a¹²* of the drum *a*, at the points where the shaft passes through the heads, there are provided bushings *i* and co-operating glands *k*, the inside of which may be connected with a source of fluid pressure so as to prevent the entrance of the material in the drum. Referring now to Fig. 4, one such source of fluid pressure is indicated at *l* as a water or oil pump, although it is evident that compressed air or steam at a pressure equal to or greater than the maximum pressure in the drum, may be substituted. In this figure is shown a pressure grease cup *m* by which the glands are lubricated.

The agitating or mixing elements include the series of blades *b* formed generally of L-shaped outline and provided with notches *b'* in their edges whereby the adjacent blades are interlocked when assembled on the shaft *c* in the manner shown in Fig. 5, and the use of bolts or other securing means is obviated except for bolts *n* which are passed through the end blades of the series and are engaged with the supporting shaft *c* to retain all of the intermediate blades in place. Where the blades are L-shaped, the supporting shaft is made square and the blade elements are alternately placed 180° apart around the axis of the shaft. The end blades *b* are provided with a supplemental blade *b²* which is preferably secured in place by means of the locking bolt *n* and is arranged to bisect the obtuse angle formed by the other two blade elements of the paddle to which it is applied. While the agitating system described would be effective in mixing the material in the area through which the blades sweep, it is evident that there is a space between the paddles and the walls of the drum in which the concrete is undisturbed and would tend to set. In order to insure the uniform mixing of the material throughout and prevent the setting thereof, auxiliary mixing elements in the form of chains *b³* are secured to the blade elements *b*, a very effective disposition of the chains being illustrated in Fig. 5. In this figure it appears that three independent chains pass from the end paddles and are secured to the next blade element of the series which is disposed at substantially 90° from the blade element to which the chain is attached. In this way, the chains extend in a substantially spiral direction from one end of the drum to the other and exert a lateral pressure on the material which tends to force it from one end of the drum toward the other. In practice, it has been found best to pass the chains through the blades elements adjacent their outer edges and to hold the chains against longitudinal movement by means of split links *b⁴* secured to the blade elements and engaging links of the chains at the points where they pass

through the blade elements, respectively. To each of the chains between adjacent points of attachment to the links b^4 , is secured another chain b^5 which may extend 5 substantially longitudinally of the drum a and may carry thereon coiled springs p , the latter being either formed in sections, as illustrated, or as a single continuous coil.

The slack in the chains b^2 and, if desired, 10 in the longitudinally extending chains b^5 , is such that during the operation of the mixer, the chains or springs engage the walls of the drum and continually dislodge the material therefrom so as to insure a uniform 15 and thorough admixture. When the speed of rotation of the blades b is below what might be termed the critical speed, the chains and springs will fall away from the walls of the drum, under the influence of 20 gravity, as they are carried up the side of the walls and will scrape the surfaces of the blades. If, however, the speed of rotation exceeds this rate, the springs and chains 25 will be maintained in engagement with the side walls at all times, under the action of centrifugal force. Under either condition, it will be evident that these auxiliary elements are actively employed in doing useful work, whether it be in scraping the 30 blades of the paddles or in removing the material from the walls of the drum. Further than that, the spirally disposed chains b^2 exert a constant lateral pressure on the material tending to force the same toward 35 the discharge end of the drum. It should be noted here that if the material is introduced into the drum a through the opening a^9 , the direction of rotation of the paddles need only be changed from time to time in 40 order to convey the material from one end of the drum to the other. It is also important that the slack in the auxiliary cleaning and feeding elements should not be so great as to permit them to become jammed 45 between the wall of the drum a and the ends of the blades b . Equivalent elements such as rods, may be employed to carry on the auxiliary scraping and mixing operations which are effected by the chains and springs 50 described.

Reference is now to be had particularly to Fig. 7 for a detail description of the discharge opening a^7 in the head a^8 of the drum a , and the means for controlling the 55 passage of the mixed material from the drum into the conveyer. On the outer face of the head a^8 is secured a casing q in which is formed a substantially annular chamber q' , which terminates in a downwardly extending discharge passage q^2 through which the mixed material and some suitable impelling gaseous element under pressure 60 (preferably steam derived through a supply pipe q^3), are discharged. In Fig. 8 is 65 shown a complete plant for carrying on the

mixing including a source of steam such as a boiler q^4 , a superheater q^5 through which the steam may be by-passed by proper manipulation of the valve q^6 , and a separator or drain q^7 . Extending through the casing 70 q is a sleeve r of somewhat greater diameter than the diameter of the discharge opening a^7 and in which is mounted slidably a piston valve, indicated generally at s , the stem of which s' is threaded into a closure block 75 r' for the sleeve r and has fastened on its free end a hand wheel s^2 to facilitate manual manipulation of the valve s . The closure block r' may be maintained in position by means of a U-bolt r^2 which is secured in 80 the outer end of the sleeve r and abuts against a shouldered portion r^3 of the block r' . The piston s proper, is preferably built up with a yielding gasket s^3 and a metallic cover plate s^4 which is adapted to fit snugly 85 within the discharge opening a^7 and have its inner face flush with the inner wall of the head a^8 of the drum a , thereby obviating the danger of a deposit of concrete or of interference with the mixing elements. The 90 gasket s^3 , when the valve is in closed position may rest against the outer wall of the head a^8 , around the periphery of the opening a^7 , and thereby effect a gas-tight closure of the said opening. 95

When the material has been thoroughly mixed, the hand wheel s^2 may be rotated to move the valve s axially in the sleeve r and open the discharge port a^7 , thus permitting the material to be forced out through this 100 opening under the influence of the spirally disposed chains b^2 and this movement is assisted in the preferred structure, by surface pressure applied to the mixture by a gaseous element introduced into the upper part of 105 the drum a , as through a valve controlled conduit t communicating with the filling dome a^2 . This gaseous element, it should be remarked, preferably is one which possesses all of the peculiar properties which are to 110 be pointed out later with respect to the conveying medium. The discharge material falls in a free stream or mass, through an opening r^4 cut in the lower portion of the sleeve r and registering with the discharge 115 duct q^2 , this opening being extended around the circumference of the sleeve for an appreciable distance so as to insure effective co-operation of the gas or vapor with the mixed material. The action of the fluid element 120 on the mass of concrete as it is discharged from the mixer may well be termed an atomizing or more properly a granulating action, in that the blast of fluid picks up the concrete and exerts a continual stress thereon 125 tending to withdraw the material from the mixer drum a and thoroughly subdivide the mass. As the concrete is picked up by the fluid blast at the opening r^4 in the sleeve r it is carried on in its granulated state 130

through the discharge duct q^2 and into the conveying conduit u to the applying nozzle v from which it is directed to the desired place of deposit. From this description it will be evident that the mixed materials are carried from the mixer to the point of deposit in the presence of (when steam is employed) an elastic gaseous element which is of such characteristics as to affect the finely divided particles of mixed material in such manner as to maintain them in proper condition during the conveying and accelerate drying and crystallization after placing. Steam, which is always available on engineering jobs requiring concrete work, is probably the most inexpensive element and, when applied in the manner taught by this invention, has been found to impart to concrete all of the properties which are recognized as being desirable.

When the desired quantity of concrete has been discharged in the manner described, the valve in pipe t may be moved to closed position and the supply of fluid under pressure may be shut off in the conduit q^3 . The pressure in the mixer drum a will then fall to that of atmospheric pressure and the flap valve a^4 may be permitted to open under the influence of gravity for the introduction of a fresh charge of materials.

The improved nozzle is indicated by the reference character v and includes manually operable clamping devices v' by which the nozzle may be formed on the conveying pipe u which is of yielding material, this being accompanied by a compression of the hose u at the end of the nozzle and a restriction of its area so that the finely divided particles of material will pass through this constricted portion and be shot out of the nozzle to the point of application with great force. The application of the material in this way is especially desirable as the particles serve to tamp the material previously applied and thereby form a dense mass. It has been found that the presence of an elastic gaseous element during the conveying of the material, after the latter has been uniformly and thoroughly mixed serves to a marked degree to prevent clogging throughout the length of the conveyer. However, there may be a slight tendency for the concrete to clog in the hose at the point where the hose u is compressed and provision is therefore made, in the form of the clamping devices v' , for the ready opening of the nozzle v to the full diameter of the hose and the release of the lodged materials at the end of the hose. After the particles have been dislodged, the nozzle may be very readily recompressed by proper manipulation of the lever.

While the preferred form of the apparatus for practising the improved method

has been described in some detail, it is to be understood that the invention is not to be limited to the precise construction shown but may be varied by the substitution of such equivalent elements as suggest themselves to those skilled in the art. Further, the improved method set forth in the appended claims may be practised in any apparatus capable of carrying out the method without departing from the scope of such claims.

The coil springs P are preferably extended so that they yieldingly press against the heads of the drum and thus keep such heads clean.

Where it is not necessary to move the conveying conduit u , it may be made of ordinary pipe. Where it is convenient to have a flexible conduit or portion of conduit, it is preferably composed of flexible hose whose interior surface is a very pure rubber or similar yielding substance.

It is found that the highly abrasive mixture does not readily attack such surfaces. In fact the rubber seems to acquire a slimy coating which acts as a lubricant. In these flexible conduits, if in sections, it is desirable to so extend the yielding interior surfaces into the couplings that no portion of the hard parts of such couplings is exposed to abrasion.

It is to be noted that upon closing the valve p , all concrete in the sleeve s is forced back into the mixer so that none remains to set and clog the discharge apparatus.

I claim as my invention:

1. Mixing the constituents of a cementitious mixture including water, applying independent pressure to said constituents while being mixed, discharging the mixed material in mass, granulating the discharged mass by means of a fluid blast independent of said mixing pressure and impelling the material in such granulated condition from the mass.

2. Mixing under steam pressure the constituents of a cementitious mixture including water, discharging the mixed material in mass, granulating the discharged mass by means of a fluid blast and impelling the material in such granulated condition away from the mass.

3. Mixing under superheated steam pressure the constituents of a cementitious mixture including water, discharging the mixed material in mass, granulating the discharged mass by means of a fluid blast and impelling the material in such granulated condition away from the mass.

4. Mixing under pressure the constituents of a cementitious mixture including water, discharging the mixed material in mass, granulating the discharged mass by means of a superheated steam blast and impelling

- the material in such granulated condition away from the mass.
5. Mixing under heat and pressure the constituents of a cementitious mixture including water, discharging the mixed material in mass, granulating the discharged mass by means of a fluid blast and impelling the material in such granulated condition away from the mass.
- 10 6. The method of mixing and placing concrete, etc., which consists in mixing the materials in a plastic condition in the presence of steam and feeding the plastic ingredients to a separate blast of steam to be caught up and carried on by the blast.
- 15 7. Apparatus for mixing and conveying concrete including a mixer drum provided with inlet and outlet openings, agitating means for the plastic conglomerate disposed operatively in the drum, said means comprising a rotatable shaft, a series of mixing blades mounted thereon and auxiliary agitating devices carried loosely by the blades and adapted to sweep through the material 20 in the zone without the area of the blades, whereby the material is uniformly and thoroughly mixed, a chamber through which the concrete passes from the outlet opening, a valve to control the outlet opening, means to 25 introduce a blast of an elastic gaseous element into the chamber to atomize the plastic ingredients, and a conduit through which the concrete is carried on by the gaseous element to the place of deposit.
- 30 8. Apparatus for mixing and conveying concrete including a mixer drum provided with inlet and outlet openings, agitating means for the plastic conglomerate disposed operatively in the drum, said means comprising a rotatable shaft, a series of mixing blades mounted thereon and auxiliary agitating devices carried loosely by the blades and adapted to sweep through the material 35 in the zone without the area of the blades, whereby the material is uniformly and thoroughly mixed, a chamber through which the concrete passes from the outlet opening, a valve to control the outlet opening, means to 40 introduce a blast of an elastic gaseous element into the chamber to atomize the plastic ingredients, and a conduit through which the concrete is carried on by the gaseous element to the place of deposit.
- 45 9. Apparatus for mixing and conveying concrete including a mixer drum provided with inlet and outlet openings, agitating means for the plastic conglomerate disposed operatively in the drum, a chamber through which the concrete passes from the outlet opening, a valve to control the outlet opening, means to 50 introduce a blast of an elastic gaseous element into the chamber to atomize the plastic ingredients, a conduit through which the concrete is carried on by the gaseous element to the place of deposit, and means for choking the said conduit to increase the effective 55 force of the blast.
- 60 9. Apparatus for mixing and conveying concrete including a mixer drum provided with inlet and outlet openings, agitating means for the plastic conglomerate disposed operatively in the drum, a chamber through which the material is passed from the outlet openings, means to introduce a blast of an elastic gaseous element into said chamber to atomize the plastic ingredients, a conduit 65 having an interior of yielding material
- through which the plastic concrete is carried on by the gaseous element, and means for choking the said conduit and allowing it to expand at pleasure for increasing the effective force of the blast and for clearing the 70 conduit.
10. A mixer for cementitious materials including a mixer drum, a rotatable shaft, a series of mixing blades mounted thereon, chains secured to said blades and extending 75 spirally of the drum, separate chains secured to the first named chains and extending longitudinally of the drum, and coil springs carried by the second named chains, all of said chains being slack and adapted to sweep 80 through the zone without the area of the blades and scrape the walls of the drum and the blades.
11. In a concrete mixer, agitating apparatus comprising a rotary shaft, a series of 85 mutually interlocking mixing blades provided with segmental angular hubs for causing them to rotate with the shaft and means for holding the said blades in their interlocked position.
12. In a concrete mixer, agitating devices comprising an angular shaft, a series of mixing blades mounted thereon and each provided with an angular bearing surface to cooperate with the angular shaft and with 95 means for interlocking the proximate blade elements, and means to secure the end blade elements of the series to the shaft to maintain the entire series in interlocked position.
13. In a concrete mixer, agitating devices 100 comprising a square shaft, a series of L-shaped blade elements mounted thereon and each provided with notches in its edges to interlock the adjacent blade elements, and locking bolts passing through the end blade 105 elements into the shaft to maintain the entire series in interlocked position.
14. A concrete mixer including a drum provided with inlet and outlet openings, a receiving chamber for the discharged concrete, and a manually operable piston disposed in said chamber and movable axially to control the outlet opening, said piston in closing adapted to drive the contents of the chamber before it.
15. A concrete mixer including a drum provided with an inlet and with an outlet opening, having a discharge port arranged to be closed by an axially moving piston and a piston for closing the port, said piston in closing adapted to move beyond said port and to drive all contents before it into the path of the mixing devices.
16. A concrete mixer including a container provided with an inlet and an outlet 125 opening, having a discharge port and a closure therefor, said closure being adapted to drive the contents of the discharge port before it into the path of the mixing devices.
17. A mixing chamber for receiving the 130

constituents of a cementitious mixture including water, means for mixing the said ingredients in said chamber, means for applying independent pressure to said constituents while being mixed, means for discharging the mixed material in mass, and means for applying a fluid blast to the said discharged mass independent of said means for applying pressure to the ingredients in

the mixing chamber for granulating the material and impelling it away from the mass.

This specification signed and witnessed this 7th day of December A. D., 1914.
